UNITED STATES PATENT OFFICE.

ROLLYN HAWKINS, OF INDIANAPOLIS, INDIANA.

DUST DEFLECTOR AND CATCHER FOR RADIATORS.

No. 818,026.

Specification of Letters Patent.

Patented April 17, 1906.

Application filed February 7, 1905. Serial No. 244,610.

To all whom it may concern:

Be it known that I, ROLLYN HAWKINS, a citizen of the United States, residing at Indianapolis, in the county of Marion and State of Indiana, have invented certain new and useful Improvements in Dust Deflectors and Catchers for Radiators, of which the following is a specification.

This invention relates to improvements in dust-catchers for radiators.

The dust and disease germs which are carried on people's shoes from our streets and are left on the carpets and floors in all residences and public buildings are kept in circulation in the air - currents that pass up through radiators in buildings heated by steam or hot water. All radiators when heated draw the dust - laden air from the floors up between the sections, thence to the top of the radiator, from whence it is diffused against the wall directly above the back of the radiator and upward to the ceiling and outward into the room. The filthy black dust is thereby deposited on the walls, ceilings, draperies, furniture--in fact, on all objects in the room, and even upon the food when that is left uncovered. This dust is not only very injurious to the wall-decorations and draperies, but is often heavily laden with germs that spread disease. It is generally found necessary to annually redecorate the walls and ceilings in steam and hot-water heated residences, flats, and other buildings. Numerous radiator "shields" and "deflectors" have been invented and tried and have uniformly failed for the reason that dust when thus shielded or deflected into the room is simply kept in circulation and will eventually settle on the draperies and decorations.

The object of this invention is to separate the dust from the air and retain it in a suitable holder, from which it can be easily removed with a damp cloth without the inconvenience of removing the dust-catcher from the radiator.

The object also is to provide a means whereby the dust-catcher can be readily removed from the radiator by simply lifting it therefrom when it is desired to do so for any purpose.

The object also is to provide means whereby the dust-catcher can be fitted to all sizes and styles of radiators.

A further object of the invention is to provide an adjustable apron at the rear of the

dust-catcher which can be set with its lower edge against the wall, where the radiators are set farther than six inches away from the wall, it not being necessary to adjust the apron when the lower edge of the latter is under six inches from the wall.

The object of the invention also is to provide a wall-protector to be placed back of the radiator where the walls are uneven by reason of panels, casings, and the like, which keep the lower edge of the apron from fitting close thereto.

I accomplish the objects of the invention by the mechanism illustrated in the accompanying drawings, in which—

Figure 1 is a detail in perspective of the upper end of the radiator, showing my dust-catcher attached in operative position. Fig. 2 is a vertical section of same. Fig. 3 is a detail in side elevation of that part of the removable fastening device which is fixed to the apron. Fig. 4 is a detail in front view of the entire mechanism used for removably securing the dust-catcher to the radiator, the view showing said parts detached from the dust-catcher and from the radiator and also showing the same without the front clamp and connecting-rod. Fig. 5 is a view in vertical section of a radiator equipped with my dust - catcher, 85 apron, and wall-protector. Fig. 6 is a detail in horizontal section on the lines 6 6 of Fig. 5. Fig. 7 is a detail in side view of the lower end of one of the end plates of the dust-catcher; and Fig. 8 is a detail in vertical section of the wall-protector, showing the means by which its upper end is secured.

Like characters of reference indicate like parts throughout the several views of the drawings.

9 represents the coils of a radiator for steam or hot water, of usual construction; and 10 is a holding-plate, preferably half-round in cross-section, to fit between adjacent pairs of radiator-coils and contact with the adjacent members of the pair, between which it is placed. 11 is a bolt which is passed horizontally between said pair of coils, first through a clamping-plate 12, placed at the front of the radiator between said same pair of coils, and then through the plate 10 in the manner shown in Fig. 2, and then said bolt is held by screwing the nut 13 upon its threaded end. The holding-plate 10 will preferably have a vertical series of bolt-holes in order that the bolt 11 may be placed higher or lower in the radiator to avoid the connecting members of the radi-

ator pairs or other obstructions that are commonly found and which vary in positions with the different styles of radiators in common use. The holding-plate 10 will preferably be 5 concave to let the nut in past its edges. The plate 10 will have a top extension, which is bent at right angles to form the horizontal member 14, that will occupy a position upon top of the radiator. This horizontal member 10 14 will terminate with a head 15 transverse to said horizontal member. The base of said head will be long enough to reach from one coil to the other of the pair above referred to 15 and will rest upon and be supported by said coils. This base of the head has a longitudinal vertical flange, with vertical grooves formed therein. The grooves are in pairs located opposite each other on the front and back sides, respectively, as shown at 16 in the 20 drawings.

17 is the hood of my dust-catcher, which may be made out of sheet steel, copper, brass, or other suitable material, plain or crimped, the crimped material being preferable for the 25 reason that it will hold its shape better, and any buckling of the metal will not be as noticeable as with plain sheet metal.

18 represents the hood ends, which are made out of cast metal and are stiff and rigid 30 in construction to give shape and rigidity to the hood which is fastened to these ends.

19 is a slotted holder which is fastened, preferably by rivets, to the under side of hood 17. This holder has a downwardly-projected 35 member provided with the under end slot 20. The slot 20 will preferably have inwardly-sloping sides and will be wide enough to receive said flange, and in operative position the inner end of the slot will bear upon the 40 top of the flange, thereby forming the principal support for the hood 17. A rocking movement of the hood is prevented by the widening of the edges of the slot into flanges, as shown in Figs. 3 and 4, which give a sufficient 45 bearing against the grooves 16 to hold the hood rigidly in position. Longitudinal movement of the hood is prevented by the formation of lugs 21, which are extended inwardly from the sides of the slot 20. These lugs enter 50 the grooves 16 in the flange of the head 15. The length of the flange is such as to receive a plurality of grooves in order that the holder may be made to fit at any part of the length 55 of the flange without any special adjustment of the distances apart of the heads 15 at each end of the radiator. This is important because the thickness of the coils may vary considerably in different makes of radiators, which would make it extremely difficult to 60 place the heads equally distant from each other in all cases. Lugs 21 are preferable to flanges for the reason that the lugs will adjust themselves without binding in the grooves under conditions that would cause a 65 flange to bind. While I have shown two lugs

extending in from each side of the slot, I have found that only one is necessary, and in practice only use a single lug.

The front of the hood 17 is bent downwardly into the half-cylindrical roll 22. It is then bent upwardly adjacent to the edge to form the member 23, and the edge of that member is bent toward the front to form the horizontal portion 24. This forms a pocket, as clearly shown in Fig. 2, into which the dust and dirt are guided by the under side of the hood, and the escape of the collected matter is prevented by the said horizontal member 24. This construction forms a very important feature of my invention. The back edge of the hood is bent down to form the approximately vertical member 26, and the edge of that member is bent to the rear to form the member 27 to make a close fit against the wall when the radiator stands quite close thereto; but when the radiator is located remote from the wall, as shown in Fig. 2, an apron 29, which is adjustable in its position, as shown in dotted lines in Fig. 2, is required to direct the current of air rising between the 90 radiator and wall into the dust-catcher. This apron is formed out of sheet metal, with a top roll or bead to receive lugs 30 from the plates 18 of the hood, thereby forming a hinge connection which makes the apron adjustable. The plates 18 are provided with openings to receive the bolts 31, by which plates 34 at the ends of the apron are pivotally connected, and the plates 18 have the slots 32 concentric with the holes for the bolts 31. The ends of the plates 34 are made concave to fit the rounded ends of plates 18, and the plates 34 have overlapping extensions 35, through which the bolts 31 are passed. The extension 35 has the bolt 38, which passes 105 through the slot 32 in the plate 18, and by means of a nut on the threaded end of said bolt the plate may be tightened so as to lock plates 34 in any adjustment that may be given. These plates have pairs of inwardly-projected lugs 33 to receive the ends of the apron and raise and lower the apron by the raising and lowering of the plates. Thus when the radiator is away from the wall so far that the dust-hood does not prevent air-currents from rising between the radiator and wall the apron 29 by the means above described can be set to close the distance in the manner as shown in Fig. 2. The apron is hinged as close to the hood as possible, so 110 as to make the joint tight between them and is therefore eccentric of the pivotal attachment of the plates 34. The apron is loosely held between the lugs, so as to slide freely between them in adjusting the apron.

115 In Fig. 5, 40 represents a molding which extends out from the wall, so as to interfere with the proper adjustment of the apron. Window-casings, pipes, and other obstructions frequently occur which makes it necessary 120 to adjust the apron. The molding 40 is provided with a slot 41, which receives the ends of the plates 34, so as to hold them in place when the apron is 125

sary in order to adapt my device to all localities to provide a false wall between the real wall and the radiator, which will be connected up with my dust-catcher, so as to direct the heated currents in front of it into the dust-catcher and prevent the heating of the air between the false wall and wall proper. This false wall, as shown in Figs. 5 and 6, comprises a vertical sheet-metal plate 41, the lower end of which rests upon the floor and the upper end of which extends up into the range of adjustment of the apron 29. It also comprises a sheet of corrugated metal 43, which is placed between the plate 40 and radiator and is separated therefrom by the horizontal metal bars 44, the bars 44 and the two metal plates being riveted together, as shown in Fig. 6. The corrugated metal 43 terminates at a suitable distance above the floor, as shown in Fig. 5, to allow the free entrance of air-currents into the open ends of the flues formed by the corrugations, and the circulation or flow of air from the rear to the front of plate 41 is permitted by a formation of holes 46 through plate 41 adjacent to the lower end of the corrugated metal sheet 43.

The upper end of the above-described false wall is held in position against the radiator by means of the metal straps 48, which are fastened by means of the bolt 11 to the radiator and which extend from thence to the top of the false wall and are bent across and down at the back of the wall in the manner as clearly shown in Fig. 8.

Having thus fully described my invention, what I claim as new, and wish to secure by Letters Patent of the United States, is—

1. In a dust-catcher for radiators, an upwardly and forwardly sloping hood having an under-side dust-catching pocket along its front edge, and an apron hinged to the rear of said hood, said apron being adjustable at its lower edge to or from the radiator.

2. In a dust-catcher for radiators, a forwardly and upwardly curved hood supported above the radiator, an apron hinged to the rear edge of the hood and adjustable at its free edge to and from the radiator, and means for holding a given adjustment of the hood.

3. In a dust-catcher for radiators, an upwardly and forwardly sloping hood supported above the radiator, said hood having an under-side pocket along its front edge with an overhanging rear flange, an apron hinged at its upper edge to the rear edge of the hood, slots in the end plates of the hood concentric with the hinge, and bolts from the apron entering said slots, and nuts on the threaded ends of the bolts by tightening which a given adjustment of the apron with relation to the hood may be held.

4. In a dust-catcher for radiators, the combination with the radiator of a holding-plate having a head with a vertically-extended flange, a hood having under-side notched

holders to engage said flanges of the head by being slipped down from above thereon.

5. In a dust-catcher for radiators, a radiator, holding-plates removably secured thereto, said plates having a head resting upon the coils of the radiator, said head having vertically-grooved flanges, a hood adapted to be supported above the radiator, said hood having under-side slotted holders to receive the flanges of said head in the slots of the holders, said slots having inwardly-projected lugs to enter the grooves of the flanges.

6. In a dust-catcher for radiators, a radiator formed of a plurality of parallel coils, a holding-plate, a bolt passing between the coils and through the holding-plate to fasten the latter to the radiator, said holding-plate having a head resting upon a pair of coils, said head having a vertically-grooved flange, a hood above the radiator, said hood having downwardly-projected slotted holders to receive the flanges of the heads in the slots of the holders, said slots having inside lugs which enter the grooves of the flanges.

7. In a dust-catcher for radiators, a radiator, a hood above the radiator and supported by the radiator, said hood sloping upwardly and forwardly and having an under-side dust-pocket along its front edge with an inwardly-projecting rear flange, an apron hinged at its upper edge to the back of the hood, and adjustable at its lower edge to and from the radiator, and a false non-heat-conducting wall at the back of the radiator in the path of the adjustable apron.

8. In a dust-collector for radiators, a radiator, a hood supported above and by the radiator, an adjustable apron hinged to the rear of the hood, and a false wall at the back of the radiator in the path of the adjustable hood, said false wall comprising a vertical plate, and a vertically-corrugated plate between the first-named plate and the radiator.

9. In a dust-collector for radiators, a radiator, a hood supported above and by said radiator, said hood being sloped upwardly and forwardly and having a collecting-pocket under its front edge, an apron hinged to the back of the hood and adjustable at its lower edge, a false wall at the back of the radiator terminating in the path of adjustable apron, said false wall comprising a vertical plate which rests upon the floor, a corrugated plate between the first plate and the radiator, and horizontal bars between said two plates, the said first plate being perforated below the corrugated plate which latter does not extend to the floor.

10. In a dust-catcher for radiators, a radiator, a hood supported above and by said radiator, an adjustable apron hinged to the back of the hood, a false wall back of the radiator terminating in the range of the adjustable apron, said false wall comprising a plate which rests upon the floor, a second corru-

gated plate between the first plate and the radiator which terminates above the floor, bars between the two plates, the first plate having perforations below the corrugated plate, and metal straps bolted to the radiator and bent up and over the top of the false wall and down against the back thereof.

11. In a dust-catcher for radiators, a hood and an apron hinged to the hood and adjustable about said hinge.

12. In a dust-catcher for radiators, a hood and an apron hinged to the hood and adjustable about said hinge and means for holding a given adjustment of the hood.

13. In a dust-catcher for radiators, a hood, an apron hinged to said hood and plates also hinged to the hood but eccentrically of the apron-hinge, and means for connecting the plates and apron whereby they will be automatically adjustable with relation to each other.

14. An attachment for radiators, comprising a hood adapted to be supported over a radiator, and a skirt extending downward from one side of the hood, the lower portion of said skirt being laterally adjustable.

15. An attachment for radiators, comprising a hood adapted to be supported over a radiator and provided with a dust-catcher, and a skirt extending downward from one side of the hood, the lower portion of said skirt being laterally adjustable.

16. In a dust-catcher, the combination with a radiator and a hood, of a member supported on top of the radiator, means depending from the member for attaching it to the radiator and means above the member for attaching the hood to the member.

17. In a dust-catcher, the combination with a radiator and a hood, of a member supported by a plurality of the radiator-coils, means depending from the member for attaching it to the radiator and adjustable means above the member for attaching the hood to the member.

In witness whereof I have hereunto set my hand and seal at Indianapolis, Indiana, this 25th day of January, A. D. 1905.
